(57) **CLAIM**

The ornamental design for a handle, as shown and described.

DESCRIPTION

FIG. 1 is a perspective view of a handle of the new design; FIG. 2 is a top plan view of the handle of FIG. 1;

FIG. 3 is a left side elevational view of the handle of FIG. 1;

FIG. 4 is a front elevational view of the handle of FIG. 1, the rear being a mirror image; and,

FIG. 5 is a right side elevational view of the handle of FIG. 1.

The portions of the Figures shown in phantom lines are not part of the claimed design and are for illustration only.
